FILTER FOR PARENTERAL FLUIDS

Stephen H. O'Leary, San Diego, and Paul J. Melton, Carlsbad, Calif., assignors to IVAC Corporation, San Diego, Calif.

Filed May 13, 1974, Ser. No. 469,223

Term of patent 14 years

Int. Cl. D23—99; D24—02
U.S. Cl. D83—1 R

FIG. 1 is a perspective view of a filter for parenteral fluids, showing our new design;

FIG. 2 is a side elevation as seen from the distal side of FIG. 1;

FIG. 3 is a side elevation as seen from the right of FIG. 2;

FIG. 4 is a bottom plan view thereof; and

FIG. 5 is an elevation as seen from the left of FIG. 2. We claim:

The ornamental design for a filter for parenteral fluids, as shown.
